RADIO RECEIVER TIME CONTROL

Clifford C. Gills, Cleveland, Ohio

Application July 8, 1941, Serial No. 401,538

5 Claims. (Cl. 250—20)

My invention relates to improvements in means adapted to be connected to a radio receiver and operated to select in advance any fifteen minute period or periods during a span of twelve hours, with regard to several different broadcasting stations, for the operation of the receiver, and the primary object of my invention is to provide a highly efficient and relatively simple arrangement of the character indicated.

Other important objects and advantages of my invention will be apparent from a reading of the following description taken in connection with the appended drawings, wherein for purposes of illustration I have shown a preferred embodiment of my invention.

In the drawings—

Figure 1 is a fragmentary face or top plan view showing the dials and selecting knob.

Figure 2 is a fragmentary enlarged transverse vertical sectional view taken through Figure 1.

Figure 3 is a transverse vertical sectional view taken through Figure 2 along the line 3—3 and looking toward the right in the direction of the arrows.

Figure 4 is a fragmentary horizontal sectional view taken through Figure 2 and on the line 4—4 looking downwardly in the direction of the arrows.

Figure 5 is a fragmentary bottom plan view of the rotatable selector ring.

Figure 6 is a top plan view of the grooved station contact annular support.

Figure 7 is a fragmentary view showing the annular station contacts.

Figure 8 is a group bottom plan view of the stationary disk and the outer stationary ring showing the radial slots therein for accommodation of the contact bars.

Figure 9 is a fragmentary transverse vertical sectional view taken through the annular station contacts and its supporting annulus and showing the contactor applied thereto, taken along the line 9—9 of Figure 2 and looking downwardly in the direction of the arrows.

Figure 10 is a longitudinal vertical sectional view taken through the clock hand assembly.

Figure 11 is a wiring diagram showing the electrical connections between the various components of the device.

Referring in detail to the drawings, the numeral 5 generally designates a suitable casing, either a portion of the radio receiver cabinet or a separate enclosure having the front or top wall 6 formed with a substantially circular opening 7 in which is seated a rotatable selector ring 8

which has at its inner edge a groove 9 resulting in a retaining shoulder bearing against the inner side of the crystal 10.

The crystal 10 which is formed of suitable transparent material has an inwardly projecting annular rib 11 adjacent its outer edge and against which the inner edge of the rotatable ring 8 bears, the rib 11 seating in an annular groove 12 in the base of the plastic or other suitable material disk 13 which includes an annular groove or channel 14 adjacent its outer edge which defines a stationary ring 15 engaging the back of the front wall 6.

The stationary ring 15 and the disk 13 have matching radial grooves 16 on the rear thereof, while the front of the disk 13 has a circular centralized recess 17.

Engaged with the back of the disk 13 and the back of the ring 15 is the annular support 18 which is formed in its frontface with circular grooves 19 seating the annular station contacts 20 flush.

Circular clock supporting plate 21 is secured to the back of the annular support 18 by means of circumferentially spaced brackets 22 which project forwardly through an opening 23 formed in a support wall 24 which is parallelly spaced from the front wall 6 to support the parts described.

30 Journaled through the rotatable ring 8 is the shaft 25 of the operating knob 26, the said shaft having a pinion 27 on its inner end for engagement with the racks of the contact bars to be described. A helical spring 28 is circumscribed on the shaft 25 between the knob 26 and the ring 8 so that when the knob is pushed in to engage the pinion 27 with one of the racks and then released the spring 28 will withdraw the pinion from engagement with the rack and restore the knob to the inoperative position shown in Figure 2 of the drawings. In this position the knob may be grasped and pushed so as to rotate the ring 8 to select the particular fifteen minute period for which broadcasting is pre-selected.

Slidable in the grooves 16 in the back of the disk 13 and stationary ring 15 are forty-eight selector bars 30 of similar construction and arrangement, the same being provided on one edge with rack teeth 31 shown in Figure 3 of the drawings so that when the pinion 27 is engaged therewith and the knob 26 rotated the bars 30 are adjusted radially with respect to the annular station contacts 20, each contact bar having a fine leaf spring 32 mounted in an accommodating

recess in the back of the bar as indicated in Figure 2 of the drawings, with a prominence arranged to engage electrically only one of the annular station contacts 20 in accordance with the position of the particular rack bar.

Thus to select the quarter hour period for broadcasting from a particular station, the operator grasps the knob 26 and swings the rotatable ring 8 around until the knob aligns with the particular hour and quarter hour marked as indicated by the numeral 33 on the outer portion of the face of the disk 13, presses the knob in to engage the pinion 27 with the corresponding rack bar 30, then rotates the knob 26 in the proper direction to cause the prominence on the leaf spring 32 to engage the one of the annular station contacts 20 corresponding to the broadcasting station selected for reception. The proper engagement of the leaf spring contact with the desired annular station contact 20 is checked by noting the alignment of the end of the selector bar, as seen through the transparent disk 13, with the proper one of the station designating circles 13' marked on the disk 13.

An ordinary electric clock mechanism generally designated 35 is mounted to the back of the supporting plate 21 and has the tubular hour hand shaft 36. The rotatable tube 36 is extended forwardly through the clock mechanism and through the disk 13 into the circular depression 17. As shown in Figure 10 of the drawings the tube 36 has rotatably mounted therein the additional tube 39 which carries the minute hand 40, the hour hand 41 being mounted directly on the tube 36. The shaft 42 which is journaled within the shaft 39 carries the stationary indicating pointer 43 in front of the disk 13 and has its opposite end operatively connected to the pulley 37 over which is trained the belt 38 which is also trained over a pulley on the turning condenser (not shown) of the radio receiver.

For manually operating the shaft 36 a suitable gear arrangement within the clock housing is operatively connected to the shaft 36, the same having a shaft extension 44 to a right angle transmission gear arrangement 45 to an operating knob 46 mounted through the walls 24 and 6 as shown in Figure 2 of the drawings. The shaft extension 42 has a ratchet wheel 44' thereon, with which is engaged a flat spring dog 45' to prevent reverse rotation of the shaft 44.

Mounted on the exterior tube 36, which makes one revolution to each twelve hours, is the contactor which is generally designated 47. The contactor 47 is arranged so that it sweeps across the exposed portions of the selector bars 30 within the opening in the annular support 18, in such a way that its spring contact finger 48 remains on each of the selector bars 30 for a full fifteen minute period and then snaps onto the next adjacent bar. The contactor 47 comprises a hub portion 49 circumposed on and secured to the outer tube 36 from which radiates a threaded tubular portion 50 in which is mounted a longitudinally adjustable screw 51 which is adjustable to tension the helical spring 52 which is circumposed on the rotatable rod 53 from which the spring contact 48 radially projects, the outer terminal of the spring 52 being wrapped as shown in Figure 9 of the drawings around the shank of the contactor 48 in a manner to force the contactor yieldably into engagement with the station contact bars 30.

A suitable transformer 55 is mounted on the side wall of the enclosure 5 above the horizontal

partition 56 as shown in Figure 2 of the drawings.

The hand switch 57 is mounted on the back of the front wall below the opening 23.

On the horizontal partition 56 are mounted in a row the trimmer condensers A, B, C and D and in front of these in a row are four relays a, b, c, and d, and in front of these the relay e.

Referring now to Figure 11 showing the electrical connections, the device is intended to operate on a 110 volt supply line including the lines 58 and 59 which are connected directly with the clock motor 35 so that the clock constantly operates. The double-pole, double-throw switch 57 includes the points 60 and 61 and 62 and 63, with the respective arms of the switch connected at 64 and 65 with the lines 58 and 59, respectively. The wire 66 leads from the point 60 to one side of the relay e, with the opposite side of this relay connected by the wire 67 with the point 62. The point 62 is also connected by the wire 68 with the primary of the transformer 55, the remaining end of the winding of the transformer being connected by the wire 69 with the switch point 63. The switch point 61 is also connected as indicated by the numeral 70 with the corresponding arm of the switch 57, which in turn is connected to the point 65 by the jumper designated by the numeral 71. The wire 72 leads from the point 61 to one side of the radio receiver (not shown). The wire 66 has a lead going to the remaining side of the radio receiver.

As shown the contact bars 30 have their spring fingers 32 engaged with one of the station annular contact 20, four of which are connected to one end of the corresponding relays a, b, c, and d, with the innermost contact 20 arranged for connection to an extra relay (not shown).

The relays a, b, c, and d have their pairs of contacts connected to the terminals of the trimmer condensers A, B, C, and D, respectively, with the trimmer condensers appropriately connected by the wires 72 and 73 with the radio receiver (not shown).

The clock motor support plate 21 is connected by the wire 74 with one end of the winding of the relay e, whereby the current is carried through the sweeping contactor 47 to the contact bars 30 and through them to the corresponding ones of the station contacts 20.

It will be obvious that when the switch 57 is turned in one way the radio receiver is connected directly to the 110 volt line and that when the switch is turned in the opposite position it energizes the transformer 55. It will be obvious that when any one of the station contacts 20 is energized in the manner indicated, current passes to the magnet of the relay in circuit therewith and then the operation of this relay cuts in the corresponding trimmer condenser into the radio circuit so as to effect the desired reception of the selected station for the selected period of time.

Although I have shown and described herein a preferred embodiment of my invention, it is to be definitely understood that I do not wish to limit the application of the invention thereto, except as may be required by the scope of the subjoined claims.

Having described the invention, what is claimed as new is:

1. A time and station selector for a radio broadcasting receiver, said selector comprising a support, a clock on said support having an hour hand shaft, a clock dial, a plurality of contact bars spaced from each other at the desired time intervals with reference to said clock dial, a sweep

contactor operated by said hour hand shaft to electrically engage with portions of said contact bars as the sweep contactor moves coordinately with said hour hand shaft, a plurality of insulated station contact strips on said support, a contact finger stationarily fixed on each of said contact bars for engagement with a selected one of said station contact strips at a time, and operating means for selectively operating a selected one of said contact bars at a time to engage its contact finger with the contact strip corresponding to the station selected, said operating means comprising a carrier mounted on said support for movement relative to said clock dial, and an operating element carried by said carrier, said operating element being movable relative to the carrier to operatively engage the contact strip selected by adjustment of said carrier relative to said clock dial, and means for adjusting said carrier relative to said clock dial.

2. A time and station selector for a radio broadcasting receiver, said selector comprising a support, a clock on said support having an hour hand shaft, a plurality of contact bars spaced from each other at the desired time intervals, a sweep contactor operated by said hour hand shaft to electrically engage with portions of said contact bars as the sweep contactor moves coordinately with said hour hand shaft, a plurality of station contact strips, a contact finger on each of said contact bars for engagement with one of said station contact strips at a time, and operating means for selectively operating a selected one of said contact bars at a time to engage its contact finger with the contact strip corresponding to the station selected, said operating means comprising a movable carrier mounted on said support, a pinion equipped rotary knob thereon, said knob and pinion being axially movable from an inoperative position, said carrier being movable on said support to select the contact bar corresponding to the beginning of the quarter hour broadcasting period to be predetermined, said contact bars having rack teeth engageable by said pinion in the operative position of the knob, whereby the selected contact bar may be moved to engage its contact finger with the station contact strip corresponding to the station selected to be received.

3. A time and station selector for a radio broadcasting receiver, said selector comprising a support, a clock on said support having an hour hand shaft, a plurality of radially arranged contact bars spaced circumferentially from each other at the desired time intervals, a sweep contactor operated by said hour hand shaft to electrically engage with portions of said contact bars as the sweep contactor turns with said hour hand shaft, a plurality of concentric station contact annuli arranged around said hour hand shaft, a contact finger on each of said radial contact bars for engagement with one of said station contact annuli at a time, and means for selectively operating a selected one of said radial contact bars at a time to engage its contact finger with the contact annulus corresponding to the station selected, said means comprising a rotatable element concentric with said hour hand shaft, a pinion equipped rotary knob thereon, said knob and pinion being axially depressible from an inoperative position, said rotatable element being rotatable to select the radial contact bar corresponding to the beginning of the quarter hour broadcasting period to be predetermined, said radial contact bars having rack teeth engageable

by said pinion in the depressed position of the knob, whereby the radial contact bar may be radially moved to engage its contact finger with the annular station contact corresponding to the station selected to be received, and an energized circuit including the operating circuit of the radio receiver, said circuit including relays related to the individual station contact annuli and trimmer condensers controlled by the relays, whereby the operating circuit of the receiver is inoperative except during the periods selected and with respect to the selected station.

4. A time and station selector for a radio broadcast receiver, said selector comprising a support, a clock on said support having an hour hand shaft, a radial sweep contactor mounted on said hour hand shaft, a clock dial surrounding said hour hand shaft, a plurality of insulated radially arranged and radially adjustable contact bars mounted on said support around said hour hand shaft and with any of which said sweep contactor can engage, said contact bars being circumferentially spaced at time intervals corresponding to divisions of time on said clock dial, a plurality of radially spaced station selecting contact rings surrounding and spaced from said hour hand shaft, a contact finger fixed on each of said contact bars for selective engagement with any one of said station selecting contact rings at a time by corresponding movement of the contact bars, and operating means on said support for operating selected contact bars, thereby determining the station and the beginning and ending for a desired period of broadcasting, said operating means comprising rack portions on said radially adjustable contact bars, a rotary carrier mounted concentrically with respect to said hour hand shaft, a manually rotatable handle carried by said carrier enabling the carrier to be rotated to a selected time position with reference to the clock dial wherein said handle is aligned with respect to the corresponding one of the radial contact bars, said rotatable handle being axially movable, said handle comprising a pinion arranged to be meshed with the rack portion of the said corresponding radial contact bar to adjust the latter with respect to said station contact rings upon moving the handle axially from a retracted to an operative position followed by rotation of the handle in the proper direction.

5. A time and station selector for a radio broadcast receiver, said selector comprising a support, a clock on said support having an hour hand shaft, a radial sweep contactor mounted on said hour hand shaft, a clock dial surrounding said hour hand shaft, a plurality of insulated radially arranged and radially adjustable contact bars mounted on said support around said hour hand shaft and with any of which said sweep contactor can engage, said contact bars being circumferentially spaced at time intervals corresponding to divisions of time on said clock dial, a plurality of radially spaced station selecting contact rings surrounding and spaced from said hour hand shaft, a contact finger fixed on each of said contact bars for selective engagement with any one of said station selecting contact rings at a time by corresponding movement of the contact bars, and operating means on said support for operating selected contact bars, thereby determining the station and the beginning and ending for a desired period of broadcasting, said operating means comprising rack portions on said radially adjustable contact bars, a rotary carrier mounted concentrically with respect to said hour hand

shaft, a manually rotatable handle carried by said carrier enabling the carrier to be rotated to a selected time position with reference to the clock dial wherein said handle is aligned with respect to the corresponding one of the radial contact bars, said rotatable handle being axially movable, said handle comprising a pinion arranged to be meshed with the rack portion of the said corresponding radial contact bar to ad-

just the latter with respect to said station contact rings upon moving the handle axially from a retracted to an operative position followed by rotation of the handle in the proper direction, said carrier comprising an annulus mounted on said support, with said handle journaled on said annulus.

CLIFFORD C. GILLS.
